CATHARINE A. GRISWOLD, OF NEW YORK, N. Y.

DESIGN FOR THE ORNAMENTATION OF CORSETS.

SPECIFICATION forming part of Design No. 18,922, dated February 12, 1889.

Application filed January 4, 1889. Serial No. 295,476. Term of patent 14 years.

To all whom it may concern:

Be it known that I, CATHARINE A. GRISWOLD, of the city of New York, county and State of New York, and a citizen of the United States, have invented and produced a new and original Design for the Ornamentation of Corsets, of which the following is a full, clear, and exact description, reference being had to the accompanying drawing, forming part of this specification.

The single figure in the drawing represents a corset in side elevation containing my new design.

The leading and special feature of my new design consists in a band or stripe extending on the corset-surface from the lower edge thereof upwardly to the waist-line, and thence with an edgewise bend upon itself returning downwardly to said lower edge, a band or stripe extending from the upper edge of the corset downwardly to the waist-line, and thence with an edgewise bend upon itself returning upwardly to said upper edge, the said bent portions of said respective bands being located opposingly to each other at said waist-line, and bands or stripes extending across and somewhat above and below said waist-line, one on each side and alongside of the opposed bent portions of the bands, extending upwardly and downwardly from the corset-edges.

A represents a corset, which may be in the usual and ordinary form.

B' represents a band or stripe extending from the lower edge of the corset A upwardly to the waist-line thereof, and thence by an edgewise bend, b', upon itself returning downwardly to said lower edge.

B represents a band or stripe extending from the upper edge of the corset A downwardly to the waist-line thereof, and thence with an edgewise bend, b, upon itself returning upwardly to said upper edge.

The bent portions b and b' of the said respective bands B and B' are located opposingly to each other below and above the waist-line, respectively.

C represents bands or stripes which are comparatively short, and are located at the waist-line of the corset, one on each side of the opposed bent portions b and b' of the bands B and B' and extending somewhat above and below the said waist-line, so that they reach alongside of said bent portions b and b'.

What I claim is—

The design for the ornamentation of a corset herein described and shown, the same consisting in a band or stripe, B', extending on the corset A from the lower edge thereof upwardly to the waist-line, and thence with an edgewise bend, b', upon itself returning downwardly to said lower edge, a band or stripe, B, extending from the upper edge of the corset downwardly to the waist-line, and thence with an edgewise bend, b, upon itself returning upwardly to said upper edge, said bent portions b and b' of said bands B and B' being located opposingly to each other at said waist-line, and bands or stripes C, located at and extending across and somewhat above and below the waist-line of the corset, one on each side and alongside of the opposed bent portions b and b' of said bands B and B'.
